UNITED STATES PATENT OFFICE.

WILLIAM L. LENGEL, OF READING, PENNSYLVANIA, ASSIGNOR TO THE NOLDE & HORST CO., OF READING, PENNSYLVANIA, A CORPORATION OF PENNSYLVANIA.

STRIPING ATTACHMENT FOR CIRCULAR-KNITTING MACHINES.

Application filed March 13, 1922. Serial No. 543,142.

To all whom it may concern:

Be it known that I, WILLIAM L. LENGEL, a citizen of the United States, residing at Reading, in the county of Berks and State of Pennsylvania, have invented certain new and useful Improvements in Striping Attachments for Circular-Knitting Machines, of which the following is a specification.

My invention relates to circular knitting machines, and particularly to attachments thereto employing thread-carrier fingers freely suspended above the needle circle and adapted to introduce additional thread or threads to the latter to be interwoven with the fabric so as to produce vertical stripes; my main object being to provide improved actuating and controlling means for accurately determining and varying the needle-engaging swings of the fingers and shifting such swings along the needle circle for producing a great variety of ornamental effects, and pattern-controlled means adapting my attachment to be employed in connection with knitting machines of the full-automatic type. The invention is fully described in connection with the accompanying drawings and the novel features are pointed out in the subjoined claims.

Fig. 1 is a side elevation indicating only the cylinder head of a well-known type of knitting machine provided with an attachment embodying my invention in preferred form; parts being shown in vertical section to more clearly disclose the construction.

Fig. 2 is a fragmentary plan view of the thread-finger suspension plate, showing two adjacent thread-carrier fingers and their actuating and controlling means, in section substantially on the line 2-2 of Fig. 3; the finger-bearing-block of one finger being removed, and parts of the mechanism of other fingers being shown.

Fig. 3 is a front elevation of a portion of the suspension plate, showing a single thread-carrier finger and its actuating and controlling mechanism, with parts of an adjacent finger mechanism; the fixed pattern-controlled contact fingers being indicated.

Fig. 4 is a side elevation of Fig. 3, partly in vertical cross-section.

Fig. 5 is a sectional plan view of a thread-carrier finger and its operating cam, taken on the line 5-5 of Fig. 4.

Figs. 6 and 7 are enlarged detail views of the pattern-controlled contact fingers for intermittently actuating the thread-carrier fingers.

Fig. 8 is a diagrammatic view showing the needle-engaging swings of the thread-carrier finger and possible variations thereof.

Fig. 9 is a perspective detail view of the finger actuating slide member.

Striping thread attachments have heretofore been employed in knitting machines and my invention relates to the general type shown in Robinson Patents Nos. 1,203,131, October 31, 1916, and 1,357,254, November 2, 1920, and consists in improved means for imparting needle-engaging swings to such thread-carrier fingers and to more certain and varied limitations of their swings, and to determinedly controlling these movements by pattern-actuated mechanism for automatically producing and changing the stripe patterns during the knitting operation.

In the accompanying drawings I have shown my improved attachment as applied to the well-known "Banner" type of circular knitting machine (Hemphill Patent No. 933,443 of Sept. 7, 1909) in which the needle-cylinder is rotated, the thread-carrier finger suspension plate being rotated with said needle-cylinder so as to maintain said fingers in constant position above their respective needles; but it will be obvious that it is equally applicable to knitting machines in which the needle-cylinder is fixed and the cam-cylinder is rotated instead, the necessary operative changes for the latter being readily provided for.

Referring now particularly to Fig. 1 of the drawings, 1 represents the usual fixed table of a knitting machine, 2 the needle-cylinder rotatably mounted thereon, 3 the non-rotatable needle-rest and cam cylinder, and 4 the stationary latch-ring showing a single needle 5, of the usual circle of needles, extending into the latter; all of which parts are of well-known construction and operation and are a sufficient showing of this well-known type of knitting machine to fully disclose the relation of my improved attachments thereto and their cooperation therewith.

My improved attachment is mainly sup-

ported on a vertical standard 10 mounted on the machine table 1, or an extension thereof, in proper position to carry the co-operative parts suspended above the needle-cylinder 2, as shown. This standard carries midway of its height, a fixed bracket 11 on which is rotatably mounted a spindle-table 12 having a vertical sleeve-bearing-extension 13, the upper end of which is 10 provided with a spidered bearing-ring 14 seating in an apertured top-bearing bracket 15 of the standard. The table 12 is provided as shown with a flange-gear 16 housed in the bracket 11 and is driven from the 15 needle-cylinder 2 by a vertical shaft 17 having gears meshing with the usual needle-cylinder driving-gear and gear 16, so as to rotate said table 12 at equal speed with the needle-cylinder 2. A single bobbin-spindle 18 and thread-guide standard 19 are shown mounted on the table 12, but it will be understood a series of these may be employed as required.

Rotatably carried by the table 12, and 25 vertically slidably in the sleeve 13, is a shaft 20, held in adjusted position therein by a set-screw 21, so as to position the thread-finger suspension plate 22 secured to the lower end of said shaft, in lowered needle-engaging position shown in full lines, or in raised out-of-the-way position indicated in dotted lines. Slidably mounted on the upper end of shaft 20 and rotatable therewith, is a sleeve 23, which slidably carries a similar 30 sleeve 24, and these sleeves 24 and 23 are respectively connected by links 25, 25 and 26, 26 extending through spidered bearing ring 14, to a flanged sleeve 27, slidably mounted on sleeve-bearing 13, and a flanged sleeve 28, 35 slidably carried by said sleeve 27, and these sleeves 27 and 28 have links 29 and 30 extending through apertures in spindle table 12, connecting them respectively to end stops 65, 66 controlling the needle-engaging 40 swings of the thread-carrier fingers as more fully hereinafter described. Forked levers 31 and 32 pivotally carried by a frame standard, as shown, respectively control the vertical adjustment of sleeves 23—28 and 45 24—27, and intermittent and determined independent movements are imparted to levers 31 and 32 through pattern-mechanism connecting rods 34 and 35.

For directly engaging the striping or embroidery thread with the needles to produce an ornamental stripe or clock design, I employ, as heretofore, a thread-carrier finger 36 similar to the fingers of the aforesaid 50 patents and freely suspended, as therein described, from a universal joint suspension head 37 seated in a bearing block 38 secured to the suspension plate 22, so that its needle-engaging finger-end 39 may freely swing about determined needles. The drawings 55 show only one finger and its individual ac-

tuating and controlling devices, which is sufficient to disclose my invention, but it will be understood the number employed may be varied to suit the requirements, for instance, Fig. 2 indicating a circular series.

Referring now particularly to Figs. 2, 3, 4, 5 and 9, which show on an enlarged scale a thread-carrier finger and its operating and controlling mechanism, it will be seen that I preferably form such finger with an intermediate integral horizontal extension 40 having a transverse slide-way 41 in one end thereof for an actuating slide member 42, the latter being adapted to contact with the surface of an actuating cam 47 and having a stud 43 engaging a transverse cam recess, as herein later described. Spring plates 44, 44 secured to the extension 40 with their free ends resting in extension recesses 40^a as shown, and projecting beyond the same across transverse slide-way 41, form a flexible connection between said finger and slide; said springs bearing on opposite ends of the slide member 42 when resting in their recesses 40^a 40^a, normally tending to move the finger and center it with relation to said slide. Transverse movement imparted to the slide-member 42, by cam 47 as later herein described, will transmit such movement to the finger 36 through said coupling springs 44, 44; and when the lateral swing of the finger is limited by end stops, hereinafter more fully referred to, such movement of the slide-member 42 will merely flex one of said springs 42 without imparting its full movement to the finger 36. The finger 36 is also provided, as shown, with an actuating extension or arm 45 from the suspension head 37, the outer end of said arm being formed with a cam-contacting head 46 engaging said cam 47 at a point at right angles to the engagement therewith of slide 42; such angular engagement positively controlling the radial swing of finger 36 and preventing its unintentional movement by centrifugal action of the rapidly rotated machine. In the drawings the finger 36 below the extension 40, is shown out of alignment with the finger portion 36^a above the latter, carrying the suspension head 37, which arrangement permits the employing of a maximum number of thread-finger units about the circle of needles, but is not an essential part of my invention.

The actuating means in my improved construction for imparting needle-engaging swings to the finger-end 39, consists of a compound cam 47 having finger-engaging cam-surfaces arranged in planes at right-angles to one another and in constant engagement with the finger-actuating slide 42, its stud 43, and finger extension head 46, so as to always positively control the movements of said slide both radially and transversely of the circle of needles; such positive

slide movements imparting positive radial needle-engaging swings to the finger 36, and transverse swings of the latter along the circle of needles through flexible connections 5 44, 44 up to the maximum of said slide movements. This cam 47, as shown, is formed with an outer cam-surface 48 substantially elliptical in shape, and having a circumferential recess forming cam-surfaces 10 49, 49 adapted to engage the stud 43 of finger-actuating slide-member 42, the latter engaging cam surface 48 which also engages the head 46 of finger-extension 45; such contacts with the cam-surface 48 being at points 15 substantially ninety degrees apart as shown, insuring their constant engagement and positive control of the finger-actuating means during the entire rotation of the cam, the surfaces 48 and 49, 49 of the latter respectively imparting radial and transverse swings to the finger-actuating slide 42,—the latter effecting positive radial swings of finger 36, and variable transverse swings of the latter through connecting springs 44, 44, 20 as above described. Both cam surfaces 48, and 49, 49, are preferably shaped, as shown in the drawings, to complete two distinct needle-engaging swings to the finger for one rotation of the cam, and each finger employed is actuated by a cam 47 rotatably mounted adjacent thereto and in proper co-operative relation therewith, said cams being intermittently rotated a half-rotation at a time by a gear 50 preferably formed integral 25 with the cam.

For simply mounting the cam 47 and its integral gear 50, I provide them, as shown, with alined bearing apertures 50^a and 50^b for engagement with trunnion projections 40 51 and 52, said projection 51 extending from the foot portion 53 of a bracket 54 secured to suspension plate 22, and projection 52 being carried by an angle-bracket 55 which, as shown, is secured to the bracket 45 54 of an adjacent finger mechanism, or may be secured directly to plate 22. The bracket foot 53 forms a bearing for a vertical shaft 56, extending through the plate 22, which shaft carries below said plate a gear 57 in mesh with gear 50, and above said plate a stud-toothed gear 58. Each finger 36 employed has a similarly mounted cam 47 and gear 58 and the latter are intermittently actuated, as shown, by a contact finger 59 50 carried in a block 60 supported from the standard 10, the finger 59 being movable into the path of the stud-toothed gears 58 carried on the rotated suspension plate 22, so as to give each gear a partial rotation on its own axis at each rotation of said plate. Two contacts 59, 59^a are shown either of which 60 may be projected against the action of its retractive spring 61, 61^a by a vertical slide cam 62, the upper finger 59^a acting only on certain stud gears 58 having extra long teeth

63 as shown, for at times operating determined fingers only instead of the entire series. The slide cam 62 is actuated at determined intervals from the pattern mechanism through connecting rod 64. 70 To control the transverse needle-engaging swings imparted to the finger-end 39 by recessed cam 47, I employ end stops 65 and 66 arranged on opposite sides of said finger-end and in the transverse path of its swing to 75 limit the finger-travel along the needle circle. These stops 65 and 66 are arranged, as shown, to contact with an enlarged finger portion 67, preferably conical in shape, so that by vertically shifting them along the 80 cone variations in the transverse swing of the finger-end 39 may be determined, both to limit the number of needles engaged and also to relatively shift the swings along the needle circle. The end stops 65 and 66 have 85 vertical extensions 65^a and 66^a respectively, as shown, slidably mounted in suspension plate 22, and to their upper ends are respectively connected the depending ends of links 29 and 30 heretofore mentioned, the latter 90 being adapted to vertically raise said stops against the action of springs 68 connecting each link to plate 22 and normally tending to move said stops in a reverse direction. The upper ends of said links 29 and 30 are 95 preferably formed as shown with return-bend portions 29^a and 30^a forming loops and are adapted to freely pass through apertures in the respective flanges of sleeves 27 and 28, to which latter they are loosely connected by 100 pins 69 engaging in said loops; this construction permitting movement of the plate 22 to the raised idle position shown in dotted lines in Fig. 1, the loops upon such movement merely idly rising through the flanges of 105 said sleeves. The drawings indicate flange 27 as controlling all end stops 65 through connecting links 29, and in like manner flange 28 controlling all end stops 66 through links 30, thus permitting independent control of each series of end stops; it will be evident however that other arrangements might be made and even individual and separate control of any end-stop employed. 110 From the foregoing description the operation of my improved attachment will be readily understood from the following brief summary and in connection with diagrammatic Fig. 8. The number of thread-carrier fingers employed, as stated, may be varied as desired, and each one is provided with an actuating cam intermittently rotated by its stud gear 58, and the transverse needle-engaging swings of the finger-end 39 120 are limited by the vertically shiftable independent end-stops 65 and 66 contacting with the conical finger enlargement 67; the movement of the stops 65 and 66 being controlled by pattern-actuated levers 31 and 32 acting 125 130

through the link-connected sleeves 23-28 and 24-27 and links 29 and 30 connecting the latter to the stop extensions 65^a and 66^a; while pattern-actuated slide 62 controls the projection of contact finger 59, or 59^a, into the path of stud gear 58 to rotate cam 47.

Whenever during regular knitting it is desired to introduce a stripe pattern in the fabric, contact 59 is projected into the path 10 of stud gears 58 rotatably carried on suspension plate 22, such projection being automatically effected by the pattern mechanism in full-automatic machines, to rotate all of said gears and their cams 47, or when contact 59^a is projected only those gears having extra long stud-teeth 63. The cams 47 will actuate the finger-ends 39 of their respective fingers 36 to engage the threads 70 carried thereby around certain needles 5, 20 which needles are determinedly selected by the pattern-mechanism through its control of slide sleeves 23-28 and 24-27 and the latter's connection to the end stops 65 and 66 so as to automatically effect any changes 25 desired. The latch ring 4, it will be seen in Fig. 1, is preferably provided with an opening 4^a through which the finger ends 39 swing in making their needle-engaging movements.

30 In Fig. 8 I have shown diagrammatically possible variations in the needle-engaging swings of the finger-end 39, dotted line 71 indicating one complete swing of said finger, the number of needles engaged being commonly varied by joint movement of the end-stops 65 and 66 to contact at different levels with the conical finger portion 67. By independently moving end stops 65 and 66, raising one and lowering the other, the number of needles engaged may remain the same, but the needle-engaging swing of the finger-end 39 will be shifted along the needle circle to include the needles in bracket 72, or by reverse movement of the stops 65 and 45 66, to include the needles in bracket 73. By differently moving the end-stops independently any determined consecutive series of the needles within the maximum transverse swing of the finger end may be engaged, providing for the production of a great 50 variety of stripe patterns or clock designs as desired.

My improved construction provides at all 65 times for imparting positive to-and-fro radial swings and determinedly varied transverse or circumferential swings to the thread-carrier finger, preventing any unintentional movement or displacement due to centrifugal force exerted by the rapidly rotated 70 plate 22; and the unit structure of each finger mechanism provides for readily adding or removing a finger, while their compact arrangement allows for the employment of a maximum number of fingers about the 85 needle circle. My attachment is readily ap-

plied to regular knitting machines of known type and the automatic actuating means may be conveniently and simply arranged to connect with a usual pattern drum mechanism so as to produce varied stripe effects during the 70 usual circular knitting operation. Modifications and changes will readily suggest themselves, and I do not desire to limit myself to the specific construction shown and described. 75

What I claim is:

1. In a striping attachment for circular knitting machines comprising a thread-carrier finger having a universal-joint suspension point, means for imparting positive 80 to-and-fro radial swings and determined transverse swings along the needle circle to the free end of said finger.

2. In a striping attachment for circular knitting machines comprising a thread-carrier finger having a universal-joint suspension point, means for imparting positive 85 to-and-fro radial swings and maximum transverse needle-engaging swings to the free end of said finger, and means for controlling said transverse swing to engage any determined consecutive series of needles within said maximum swing.

3. In a striping attachment for circular knitting machines comprising a thread-carrier finger having a universal-joint suspension point, means for imparting positive 95 to-and-fro radial swings and varying transverse swings to the free end of said finger, and means for determinedly shifting 100 said swings along the needle circle.

4. In a striping attachment for circular knitting machines comprising a thread-carrier finger having a universal-joint suspension point, means for imparting positive 105 to-and-fro radial swings and maximum transverse needle-engaging swings to the free end of said finger, vertically-movable finger-contacting end stops, and means for independently moving said stops to engage 110 any determined consecutive series of needles within said maximum transverse swing.

5. In a striping attachment for circular knitting machines comprising a thread-carrier finger having a universal-joint suspension point, means for imparting intermittent needle-engaging swings to the free end 115 of said finger comprising a compound cam adapted to impart a positive radial swing and a maximum circumferential swing 120 thereto, and means for varying said circumferential swing.

6. In a striping attachment for circular knitting machines comprising a thread-carrier finger having a universal-joint suspension point, means for imparting intermittent 125 needle-engaging swings to the free end of said finger comprising a cam having finger-engaging cam surfaces in constant engagement with said finger. 130

7. In a striping attachment for circular knitting machines comprising a thread-carrier finger having a universal-joint suspension point, means for imparting intermittent needle-engaging swings to the free end of said finger comprising a cam having finger-engaging cam-surfaces arranged in planes at right-angles to each other. 10
8. In a striping attachment for circular knitting machines comprising a thread-carrier finger having a universal-joint suspension point, means for imparting needle-engaging swings to the free end of said finger comprising a cam having a finger-engaging cam-surface and a recess in said surface forming a cam track for said finger at right-angles to said cam surface. 15
9. In a striping attachment for circular knitting machines comprising a thread-carrier finger having a universal-joint suspension point, means for imparting needle-engaging swings to the free end of said finger comprising a compound cam having a finger-engaging cam-surface adapted to impart positive to-and-fro radial swings to said finger, and a right-angled finger-engaging cam surface adapted to impart maximum circumferential swings to said finger, and means for varying said circumferential swings. 20
10. In a striping attachment for circular knitting machines comprising a thread-carrier finger having a universal-joint suspension point, means for imparting intermittent needle-engaging swings to the free end of said finger comprising a rotary cam mounted adjacent and in constant engagement with said finger, and means for imparting intermittent motion to said cam. 25
11. In a striping attachment for circular knitting machines comprising a thread-carrier finger having a universal-joint suspension point, means for imparting intermittent needle-engaging swings to the free end of said finger comprising a rotary cam mounted adjacent said finger and having cam-surfaces engaging the latter at two separate points. 30
12. In a striping attachment for circular knitting machines comprising a thread-carrier finger having a universal-joint suspension point, means for imparting intermittent needle-engaging swings to the free end of said finger comprising a rotary cam mounted adjacent said finger and having right-angled points of contact with the latter. 35
13. In a striping attachment for circular knitting machines comprising a thread-carrier finger having a universal-joint suspension point, means for imparting intermittent needle-engaging swings to the free end of said finger comprising a rotary cam having finger-engaging cam surfaces in planes at right-angles to each other, said cam being mounted adjacent said finger and having right-angled points of contact with the latter. 40
14. In a striping attachment for circular knitting machines comprising a thread-carrier finger having a universal-joint suspension point and a fixed and a movable actuating extension, means for imparting intermittent needle-engaging swings to the free end of said finger comprising a rotary cam having cam-surfaces engaging said fixed and movable finger extensions. 45
15. In a striping attachment for circular knitting machines comprising a thread-carrier finger having a universal-joint suspension point and a fixed and a movable actuating extension, means for imparting intermittent needle-engaging swings to the free end of said finger comprising a compound rotary cam mounted adjacent said finger and having one cam-surface engaging both said fixed and movable finger extensions, and a second cam-surface engaging said movable finger extension only. 50
16. In a striping attachment for circular knitting machines comprising a thread-carrier finger having a universal-joint suspension point and a finger-carried actuating extension transversely movable thereon and adapted to impart circumferential swings to said finger end, means for intermittently reversely moving said extension, and finger-contacting stops adapted to determinedly limit the swinging movement imparted to said finger end. 55
17. In a striping attachment for circular knitting machines comprising a thread-carrier finger having a universal-joint suspension point and a finger-carried transverse slide-member having flexible finger-actuating connections adapted to impart transverse swings to the free end of said finger, a rotary cam mounted adjacent said finger and having a cam-surface in fixed engagement with said slide-member, and finger-contacting stops independently movable to determinedly limit the swinging movement imparted to said finger end. 60
18. In a striping attachment for circular knitting machines comprising a thread-carrier finger having a universal-joint suspension point and an enlarged finger-portion of tapered cross-section, means for imparting intermittent needle-engaging swings to the free end of said finger, and stops movable into the path of said finger to engage different portions of said taper to determinedly limit the needle-engaging swings of the finger end. 65
19. In a striping attachment for circular knitting machines comprising a thread-carrier finger having a universal-joint suspension point and a conical contact portion, means for imparting an intermittent maximum needle-engaging swing to the free end. 70

of said finger, and end stops independently movable to contact with different portions of said cones to limit said swing to engage any determined consecutive series of needles 5 within said maximum swing.

20. In a striping attachment for circular knitting machines comprising a thread-carrier finger having a universal-joint suspension point; means for imparting positive to-
10 and-fro radial and maximum transverse needle-engaging swings to the free end of

said finger, means to control said transverse swing to engage any determined consecutive series of needles within said maximum swing, and pattern-controlled actuating 15 means adapted respectively to intermittently actuate said needle swinging means and to independently adjust said finger control means during continuous circular knitting.

In testimony whereof I affix my signature.

WILLIAM L. LENGEL.
